DOUBLE ACTING ENGINE

Arthur J. Paige, Detroit, Mich.

Application August 6, 1931. Serial No. 555,390

3 Claims. (Cl. 123—57)

This invention relates to internal combustion engines employing reciprocating pistons and more particularly to engines of the double acting type.

5 An object of this invention is an engine including a block having a cylindrical bore and a coaxial cylindrical counterbore, the block having passages leading into the counterbore, for admitting an explosive mixture thereto, at the 10 lower and upper ends of the latter. Slidably disposed within the bore and counterbore of the block is a hollow trunk piston having an annular ledge at its upper end. The skirt of the piston slidably engages the wall of the bore and the ledge slidably engages the wall of the counterbore. As the explosive mixtures, introduced as 15 above described, are ignited alternately, force is imparted to the piston, first on the under side of the ledge to drive the piston upwardly, and 20 then on the top surface of the ledge to drive the piston downwardly. Above the block is a water cooled jacketed head having a cylindrical water filled part projecting into the piston thru the top 25 end of the latter. Connected to the piston near its lower end and projecting thru the latter is a connecting rod which may be connected to a crank in the usual manner.

If desired, the upper portion of the piston skirt is made slightly smaller than the lower portion 30 so it will clear the upper wall of the bore.

Still further objects will readily occur to those skilled in the art upon reference to the following description and the accompanying drawing in which

35 The figure shows in cross section an embodiment of the invention.

Referring to the drawing, it will be seen that there is provided a block comprising two parts, denoted 10 and 11, respectively, these parts being 40 bolted to and engaging each other on the parting line indicated at 12. The part 10 is provided with a cylindrical bore 14 and the part 11 is provided with a cylindrical counterbore 16 coaxial with the bore. The walls of the block parts 10 and 45 11 are made hollow so as to provide jackets for the cooling medium, indicated at 18 and which in general, is water. A head 20 is disposed above the block and is secured thereto by bolts, the head and block engaging on the parting line 22. 50 Disposed within the bore and counterbore is a piston 26 having open ends and having at its upper end an annular ledge 28. The latter is of such a diameter that as the piston reciprocates in the bore and counterbore the ledge slidably engages the wall of the counterbore 18, and the 55

lower portion of the piston skirt, slidably engages the wall of the bore 14. The portion between the ledge and the lower portion of the skirt is made slightly smaller than the latter, so that as the piston reciprocates, the upper portion will clear the wall of the bore 14, in a manner readily seen.

The block is provided with passages 30 and 32 controlled by valves 33 and opening into the counterbore. These passages which are like the usual inlet valve passage in the ordinary automobile cylinder block admit explosive mixture into the counterbore alternately, the valve being properly timed for this purpose. When the mixture in the counterbore below the ledge 28 explodes due to the action of the spark plug 36, 60 force will be imparted against the under surface of the ledge 28, driving the piston upwardly to pull the connecting rod upwardly. Similarly when the mixture in the counterbore above the ledge 28 explodes, due to the action of the spark plug 39, force will be imparted against the upper surface of the ledge, driving the piston downwardly and imparting a downward thrust upon the connecting rod.

Suitable cams indicated at 40 and mounted 65 upon cam shaft 41 are provided to actuate the valves 33.

An important feature of the invention resides in the construction of the head 20. The latter is provided with a cylindrical cup shaped part 80 46 which is disposed within the hollow piston, projecting thru the open end of the latter. The interior wall of the piston engages the exterior of this cylindrical part and as the piston reciprocates it is correspondingly guided by the latter as 85 well as by the engagement of its skirt and its ledge with the walls of the bore and counterbore.

Further the cylindrical part 46 of the head being filled with a cooling medium such as water, cools the piston effectively as can readily be seen. 90

While exhaust passages, exhaust valves, etc. have not been shown, it will clearly be understood that such are intended to be provided, the disclosure being merely indicative of applicant's improvement per se.

Now having described the invention and the preferred embodiment thereof, it is to be understood that the said invention is to be limited, not to the specific claims herein set forth, but only by the scope of the claims which follow:

What I claim is:

1. In a reciprocating piston type internal combustion engine, a cylinder block having a cylindrical bore and a coaxial cylindrical counterbore, a reciprocating piston in said bore and

100

105

110

counterbore and having an annular ledge, integral with the skirt of the piston and slidably engaging the wall of said counterbore, the skirt of the piston slidably engaging the wall of the bore, and a jacketed head disposed on said block and covering the bore and counterbore, the upper part of the piston skirt having an external diameter slightly less than that of the lower part of the piston skirt whereby the upper part will clear 10 the wall of the bore, as the piston reciprocates.

2. In an internal combustion engine having a crankcase, a crank shaft and a connecting rod therein, a guide cylinder mounted on said crankcase and into which said rod extends, cooling 15 means for said cylinder, a guide piston in said cylinder connected to said rod and provided with packing rings, said piston being open at its upper end, an operating cylinder of larger diameter mounted upon and coaxial with the guide cylinder and having a lateral combustion chamber at each end thereof, external and internal cooling means for said operating cylinder, the internal cooling means comprising a cylindrical concentric portion extending therewith from above to 25 substantially the lower end of said operating cylinder and being of smaller diameter thereby providing an annular chamber, an extension on said piston having an annular shoulder substantially coextensive in area with said chamber, said piston 30 being closed at its upper end by said cylindrical

concentric portion of the cooling means, and being substantially cylindrical throughout its length below said shoulder with that portion operating only in the guide cylinder having a slightly greater diameter than the portion operating in the operating cylinder. 80

3. In an internal combustion engine having a crankcase with a cylinder mounted thereon, said cylinder having cooling means, an operating cylinder mounted thereon in axial alignment therewith and of larger diameter than the first mentioned cylinder, said larger cylinder having a combustion chamber open to each end thereof, cooling means for said operating cylinder including external cooling means and a jacketed head having a cylindrical portion extending into said operating cylinder substantially the full length thereof but spaced from the cylinder walls to form an annular chamber, and a stepped open end piston having a portion operating in the first mentioned cylinder and a portion of larger diameter operating in the operating cylinder in said annular chamber, said piston being closed by the cylinder head portion, there being packing means between the walls of both cylinders 100 and the adjacent piston surfaces and between the cylindrical head extension and the inner wall of said piston adjacent thereto. 95
